DESIGN FOR A RADIO CABINET

Stuart J. Cardoza, Berkeley, Calif.

Application January 25, 1937, Serial No. 67,273

Term of patent 7 years

To all whom it may concern:

Be it known that I, Stuart J. Cardoza, a citizen of the United States, residing at Berkeley, in the county of Alameda and State of California, have invented a new, original, and ornamental Design for Radio Cabinets of which the following is a specification, reference being had to the accompanying drawing forming part thereof.

Fig. 1 is a perspective view of the radio cabinet, showing my new design;

Fig. 2 is a front elevational view;
Fig. 3 is a side elevational view; and
Fig. 4 is a plan view.

I claim:
The ornamental design for a radio cabinet as shown.

STUART J. CARDOZA.
